UNITED STATES PATENT OFFICE.

PAUL E. GERHARD, OF LEBANON, PENNSYLVANIA, ASSIGNOR TO LEBANON STEEL FOUNDRY, OF LEBANON, PENNSYLVANIA, A CORPORATION OF PENNSYLVANIA.

FLANGEWAY GUARD FOR HIGHWAY CROSSINGS.

Application filed January 15, 1927. Serial No. 161,265.

This invention relates to improvements in flangeway guards for highway crossings.

It is an object of this invention to make up each flangeway guard of suitable short length sections so that the required number of sections may be furnished to provide different lengths of guards for different lengths of highway crossings which vary anywhere from twenty feet to one hundred feet, more or less, in track rail direction length.

In accordance with this invention, each flangeway guard includes, almost invariably, a plurality of intermediate sections. These intermediate sections are aligned, in highway crossing installations; and each end section of an alignment of a plurality of sections is connected with an end section having a head, the outward end of which tapers downwardly to its free end, this tapered end section being also outwardly flared. Thus, in accordance with this invention, each flangeway guard includes one or more endwise aligned, intermediate sections and two therewith connected end sections, each of which has a downwardly tapered top surface and outwardly flared free end portion. The upstanding webs of the intermediate and end sections are provided with openings along their lengths for interlocking reception of plastic paving material. All the sections have horizontal base flanges provided with holes, through which the sections are spiked to crossties, one set of sections being located inwardly of one, and the other set of sections being located inwardly of the other, track rail. The end sections are made as rights and lefts, but are otherwise identical; and bracing means are provided as hereinafter explained. Each section includes a base flange spikable to crossties, and an integral upstanding web having an integral head.

In the accompanying drawings, forming a part hereof and illustrating the invention,

Fig. 1 is a transverse vertical section, at line 1—1 of Fig. 3, showing a track rail and flangeway guard installation containing the present invention, on a crosstie.

Fig. 2 is an elevational view showing a pair of track rails with a pair of flangeway guards installed between them.

Fig. 3 is a top plan, diagrammatic view, on a small scale, of an installation such as indicated in Fig. 2, the view showing each flangeway guard terminating at each end in

a downwardly tapered and inwardly flared, 55 end section.

Fig. 4 is a view on a larger scale, similar to that of Fig. 3 but it shows only one end section of each flangeway guard and further shows transverse bracing for the flangeway 60 guards instead of bracket bracing, such as shown in Figs. 2 and 3.

Fig. 5 is a partial inward side elevation of an intermediate flangeway guard section and portions of thereto connected end sections. 65

Fig. 6 is a transverse section at line 6—6 of Fig. 5 and illustrates a tongue and socket joint structure between abutted ends of an intermediate section and an end section.

Fig. 7 is a plan of a right hand end section. 70

Fig. 8 is a side view of a right hand end section.

Fig. 9 is a plan view of a left hand end section. 75

Fig. 10 is a side view of a left hand end section.

Fig. 11 is a perspective view of a railway track, highway crossing provided with flangeway guards such as shown in the preceding figures, paving material being shown between the flangeway guards and having its edges interlocked with said guards through lengthwise extending openings in the upstanding webs of the flangeway guard sections. 85

Fig. 12 is a perspective view illustrating a modification in which an intermediate section has an out-turned head forming an under recess in which an end of a projecting, 90 interlocking tongue is welded. This shows a portion of the transverse brace illustrated in Fig. 4.

Fig. 13 is a perspective view similar to Fig. 12 but shows a bracket brace in place. 95

Fig. 14 is a perspective view similar to the views in Figs. 12 and 13, but shows a bracket brace having a cross head adjacent which the shank of the brace passes through opposed recesses in the abutted ends of an intermediate and an end, section. 100

Fig. 15 is a perspective view illustrating a different cross-sectional form of a guard section.

Figs. 16, 17, 18 and 19, also, respectively 105 show different cross-sectional forms of a guardway section.

Fig. 20 is a perspective view showing

two intermediate sections connected together by the cross head of a bracket brace. The view also shows an intermediate section and an end section connected together by the ends of the cross head of the bracket brace.

Fig. 21 is a perspective view of another form of bracket brace detached.

In the drawings, the intermediate portion of each flangeway guard is indicated by A applied to the inwardly turned, horizontal base flange of each constituent section; and each end section of each flangeway guard is indicated by A¹ applied to its inturned, horizontal base flange. In each guard, the intermediate portion has aligned with it, and in contact with each of its constituent end sections, one of the end sections A¹, the free end portion of each end section A¹ having a head that tapers downwardly in the direction of its free end wall and that also flares inwardly away from the adjacent side of a track rail. Crossties are indicated by 1; a rail plate by 2, a track rail base by 3, and a track rail head by 4.

Inwardly and spaced apart from each track rail there is mounted a flangeway guard, having an intermediate portion which includes a plurality of intermediate sections A, the horizontal base flanges of which extend inwardly; that is, in a direction away from the adjacent track rail. Each section A¹ includes an upstanding outwardly and upwardly slanting web 5 integral with the base flange and which, at each end, merges with a vertical web 6 also integral with the base flange. The base flanges of the sections A and of the two end sections A¹ are provided with a series of spike receiving holes, and the base flange of each section is spiked at 7 to a crosstie adjacent but spaced inwardly apart from the rail plate and track rail. Each end web 6 of an assemblage of intermediate sections is provided with a horizontal bolt hole 8 for reception of a threaded clamping bolt 9, the head 10 of which bears on the outward surface of a vertical web 6. The threaded end 9 of the bolt is provided with a nut 11 which clamps against the horizontal end 12 of a bracing member in contact with the inner side of a web 6. The horizontal end 12 of the bracing member may be, as shown in Figs. 1, 2 and 3, the upper end of a bracket brace 13, the other end 14 of which is horizontal and spiked at 15 to a crosstie. Any number of these bracket braces 13 may be used along the inward side of each flangeway guard throughout the length thereof, as desired. By locating each flangeway guard in its entirety and its respective braces between a pair of track rails, the track rails may be removed at any time without the necessity of removing any portion of the flangeway guard installation; and these bracket braces 13 which are extended from an upper por-

tion of a web 6 downwardly and inwardly to the crosstie, bracingly connect the flangeway guard and the cross tie and are embedded in the paving material P (Fig. 11) and are thus removed from injurious contact by loaded vehicles travelling over the highway crossing.

In the forms of the invention shown in Figs. 1 to 10, inclusive, the free end portion of each assemblage of intermediate sections is provided, near its head, with an integral, horizontal, projecting tongue 16; and the inner end of each end section A¹ is provided with a horizontal tongue receiving recess 17 in its head. The heads of all the sections in each guard are aligned, except at the free end portion of each end section. Each end section A¹ has a web 5^a in alignment with the web 5 of an intermediate section A and has a vertical web 6^a aligned with the web 6 of an intermediate section. The web 6^a of the end section has a bolt receiving hole 8^a, in horizontal alignment with the bolt hole 8 of the end section, and the horizontal upper end 12 of a bracket 13 laps each two adjacent webs 6 and 6^a whereby the abutting ends of the intermediate section and of an end section are tied together in their lengthwise directions. The tongues 16 of an intermediate section adjacent an end section are entered severally in a socket 17 of an end section, preventing upward displacement of the interlocked sections, relatively one to another; the walls of sockets 17 extending above and below the tongues.

Each intermediate section A and each end section A¹ is provided with a series of openings 18 through which the plastic paving material will project for anchorage of the edges of the paving in the flangeway guards.

As shown in Fig. 4, the horizontal, bent ends of a transverse brace or tie-bar 19 may be bolted to adjacent section webs 6 or 6 and 6^a. At the adjacent section webs 6 and 6^a, the bent ends are indicated by 20 and correspond to the horizontal ends 12 of the bracket brace 13. Like the bracket braces, the transverse braces are embedded in the paving material. The heads 21 of the intermediate members are integral with their upstanding webs and such webs are integral with the base flange. Said heads 21 are aligned one with another; and also with the inturned portion 22 of the heads of the end sections A¹, the outer portions of these heads tapering at 23^a downwardly and flaring inwardly at 23 as best shown in Figs. 7 to 10, inclusive. The inturned portions 22 of the heads of the end sections, their upstanding webs and base flanges are all integral one with another. The spike holes through the base flanges of sections A and A¹ are indicated by 14^a. The constituent sections A of the intermediate portion of the flange-way guard, between its two end sections A¹, are

mechanically locked together by a horizontal brace member end 12 or 20, according to the forms of brace used; and for the purpose of this invention, in its broader aspect, the 5 sections are considered as being united by lengthwise extending tie-plates, brace member ends 12 and 20 forming such tie-plates and the same overlapping each of two abutting sections and being bolted in place. Such 10 bolted tie-plates also resist and prevent vertical displacement of the abutting ends of the sections.

The base flanges of all the sections project from the inward side of their webs so that 15 the heel portion of each section is nearest the adjacent track rail; and the base flanges are all mounted flatwise on the crossties and spiked directly thereto, out of contact with the rail plates and track rails in order that 20 the sections of the flangeway guards, and each guard in its entirety, may be installed out of metallic contact with rail plate and track rails to prevent or minimize short circuiting of railway safety signal currents in 25 track rails. In all forms of the invention, whether the braces are bracket braces as shown in some of the figures or are of horizontal tie rod or tie plate construction, the braces are embedded in the paving material 30 and thereby held downwardly. Such embedment of the braces not only prevents wheels of vehicles moving across the railway crossings from injuring or loosening the braces, but also prevents the braces from 35 rising upwardly under any upward spring of end portions of the flangeway guard members. In the preferred construction, the top flange of the upstanding web of each flangeway guard section turns outwardly in 40 the direction of the base flange, both flanges projecting away from the rail opposing side of the web of each member. By the term rail opposing side is meant the inward side of each flangeway guard section that is installable adjacent a side of a track rail.

In Fig. 12, sections A and A¹ are shown connected by an end 20 of a transverse brace or tie-bar. The cross sectional contours of sections A and A¹ differ from the cross sectional contours above mentioned. Web 24 is vertical and has its upper, margin 25 turned over, outwardly along its length. An interlocking tongue 26 has an end portion 27 welded in place under the outwardly turned flange 25. Similarly, at the joint between sections A and A¹, this interlocking tongue arrangement is shown both ends of the tongue being welded in place.

In Fig. 13, the cross sectional contour of 60 the sections is the same as that shown in Fig. 12, but in this case one of the bracket braces is used instead of the transverse brace.

In Fig. 14, the cross sectional contours of the sections A and A¹ are the same 65 as those shown in Figs. 12 and 13, but a

bracket brace 28 having a rigid cross head 29 and a base flange 30 is spiked at 31 to the crosstie. The shank of the bracket, back of the head, passes through opposed recesses at 28^a, the cross head ends being welded or otherwise fixed to an opposed wall of the section. The shank 28 by passing through the opposed recesses prevents displacement of the abutted end sections relatively one to another. The under walls of the recesses 75 form bearings for the under side of the shank where it passes through the recesses. The cross head of the bracket brace is positioned on the outward side of the meeting ends of the two flangeway guard sections. Thus 80 each bracket serves to connect two, endwise abutted, flangeway guard sections to a cross tie or other track rail support, and also to connect the endwise abutted, flangeway guard sections endwise, and also to prevent upward displacement of the ends, either or both, of the endwise abutted, flangeway guard sections.

In Fig. 15, I show a section A of cross sectional contour different from that of any section above mentioned. In this case, the section has a vertical web 32 and a flat base 33; its head is turned over in the direction of the rail forming a bend 34 which terminates in a horizontal flange 35 the edge of 90 which is opposed to the adjacent rail.

In Fig. 16, I show still another cross sectional form of a section A, in which the web 36 slants upwardly and outwardly from its flat, spikable brace flange 37 and merges 100 into an upstanding, inwardly extending portion 36^a having a horizontal, inwardly turned, flange forming head 38. The horizontal, outwardly extending flange 36^a when in an installation faces the adjacent rail 105 web.

In Fig. 17, I show still another cross sectional contour of a section A. In this section, the vertical web 40 has a spikable, horizontal, brace flange 41, the web at its 110 head being turned downwardly and upwardly at 42.

In Fig. 18, I show still another cross sectional contour of a section A in which the web 43 has a horizontal, flat spikable base 115 flange 44, the web 43 extending upwardly into a lengthwise troughed portion 45 provided with an inturned, horizontal head 46.

In Fig. 19, I show still another cross sectional contour of a section A in which the web 47 slants upwardly and outwardly and has a horizontal base flange 48 spiked to a crosstie; terminates upwardly in an inturned head 49, and is provided along its side adjacent the rail with a lengthwise trough shaped flange 50.

The structures shown in Figs. 1 to 10, inclusive, are preferably castings. The guard rail sections shown in Figs. 12 to 19, inclusive, are preferably rolled shapes.

The different cross sectional shapes or contours of the sections are shown in order to indicate more clearly the fact that flangeway guards, embodying my invention, may 5 be made in a variety of shapes without departure from my invention. Furthermore, the various shapes may be made by drop forging instead of by casting or rolling.

The cross sectional shapes of the sections 10 A, illustrated in all the figures herein described may be used in connection with section A¹ of approximately the same cross-section.

Advantages of flangeway guards embodying my invention, are: They can be 15 made in sections, the end sections being rights and lefts so that a series of sections can be aligned, endwise interlocked or connected by tie-plates; and also braced between a pair of the flangeway guards, either 20 by the bracket braces spiked to the crossties or by the transverse tie-bar form of brace above described; the spiking of the flangeway guard members or sections directly to 25 the crossties, without engaging them with any of the railway track elements, other than the crossties; and the interlocking plastic pavement with the flangeway guard webs by projection of the paving material 30 through the lengthwise series of openings therefor in the opposed webs of the flangeway guards.

The bracket brace 28 shown in Fig. 14 is, for many installations, the best form of brace 35 known to me. The ends of the cross head, as shown in Fig. 14, are preferably welded in place as above described, but the cross head may be used whenever desired with each of its ends inserted in a horizontal 40 socket comparable to 17, such socket being formed in the ends of sections that are to be abutted. In other words, while in Fig. 5 the tongue 16 is integral with an intermediate section, yet obviously the intermediate 45 section may be formed with a socket 17 complementary to the one shown in Fig. 6. The bracket brace 28 is shown detached in Fig. 21 and is illustrated in Fig. 20 with the ends 28' of its cross head in opposed recesses, one in the end of an intermediate section and one in the inward end of an end section. The bracket braces, as well as the 50 cross ties may, of course, be used in connection with the meeting ends of intermediate sections.

Some features of my invention shown in the drawings and above described are not herein claimed as they are also set forth and form a part of the subject matter of my application Ser. No. 197,774 filed the 10th day of June, 1927. This latter application is in the nature of a division of this present application.

What I claim is:

65 1. As a new article of manufacture, a

flangeway guard comprising alined sections two of which are right and left hand end sections, each end section having a downwardly tapered and outwardly flared end portion, and means for lengthwise connecting abutting ends of said sections; each section having an upwardly extending web, a base flange integral therewith and provided with holes for the passage of fasteners; said web having an integral top flange, said flanges extending throughout the length of the web and projecting away from the web in the same direction; means for lengthwise connecting said members together in the lengthwise direction at opposed ends of said members; and other means engaging the webs of adjacent members at the opposed ends of said members, for preventing upward displacement of one member in relation to another.

2. As a new article of manufacture, a flangeway guard comprising alinalbe sections two of which are right and left hand end sections, each end section having a downwardly tapered and outwardly flared end portion; and means for lengthwise connecting abutted ends of said sections; each section having a base flange provided with holes for passage of fasteners, an integral upstanding web and a therewith vertical integral top flange; and said means being adapted to prevent upward displacement of the connected ends of the sections, said flanges projecting inwardly of the sections, and the abuttable end portions of the sections being provided with bolt holes.

3. As a new article of manufacture, a flangeway guard including a plurality of lengthwise alinalbe sections two of which are right and left hand end sections; each section having a horizontal base flange provided with holes for passage of fasteners, and each end section having an integral slanting top which is flared inwardly; and tongue and socket means for connecting an end section with a section between it and the other end section.

4. The combination with track rail supports, of a pair of laterally spaced apart flangeway guards each made up of a plurality of sections two of which are right and left hand end sections, and each having a base flange provided with fastener receiving holes; fasteners for holding the base flange on the rail supports; and flangeway guard bracing means located between said guards.

5. The combination with track rail supports, of a flangeway guard including a plurality of aligned and abutting sections each section having a base flange and an upstanding web; a tie-plate overlapping a joint between two abutted sections; and means for clamping each end of the tie-plate to a section.

6. The combination with track rail sup-

ports, of a flangeway guard including a plurality of aligned and abutting sections each section having a base flange and an upstanding web; a tie plate, and means for clamping each end of the tie-plate to a section, the tie-plate forming part of a brace having an end anchored at an inward side of the flangeway guard.

7. In a flangeway guard construction, the combination with a pair of alined and endwise opposed, guard forming members, of a horizontal connecting bar uniting adjacent end portions of said members, and means to prevent upward movement of said members relatively to said bar, when in use.

8. In a flangeway guard construction, the combination with a pair of alined and endwise opposed, guard forming members, of a horizontal connecting bar uniting adjacent end portions of said members, and means to prevent upward movement of said members relatively to said bar, when in use; said bar being fixed and projecting from an end of one of said members, and the other member having a socket in which the projecting end of said bar is received.

9. In flangeway guard construction, the combination with track rail supports and track rails, of alined, endwise opposed flangeway guard members; and means, for connecting said members together in the lengthwise direction, at opposed ends of said members, and other means located at the opposed ends of said members for preventing upward displacement of the connected ends of said members relatively one to another.

10. The combination with cross-ties for railway track rails; rail plates, and track rails, of a pair of laterally spaced apart flangeway guards each made up of a plural-

ity of sections two of which are right and left hand end sections, each section having a base flange provided with fastener receiving holes and extending in a direction away from an adjacent track rail; fasteners for holding the base flange directly on the rail supports and out of contact with adjacent rail plates and track rails; and flangeway guard bracing means located between said guards.

11. The combination with cross-ties for railway track rails; rail plates, and track rails, of a pair of laterally spaced apart flangeway guards each made up of a plurality of sections two of which are right and left hand end sections, each section having a base flange provided with fastener receiving holes and extending in a direction away from an adjacent track rail; fasteners for holding the base flange directly on the rail supports and out of contact with adjacent rail plates and track rails; and flangeway guard bracing means located between said guards; and, between said flangeway guards, paving material embedding the bracing means; said bracing means being detachably connected with the flangeway guards.

12. The combination with track rail supports, of a flange-way guard including a plurality of aligned and abutting sections each section having a base flange and an upstanding web; a tie plate; and means for clamping each end of the tie plate to a section, the tie plate forming part of a brace having an end anchored at an inward side of the flangeway guard; and paving material in which said brace is embedded.

Signed at Lebanon in the county of Lebanon and State of Pennsylvania this 31st day of December, A. D. 1926.

PAUL E. GERHARD.
